UNITED STATES PATENT OFFICE

124,532

DESIGN FOR A MERCHANTISE CABINET

Charles E. Knox, Enid, Okla.

Application October 5, 1940, Serial No. 95,665

Term of patent 14 years

To all whom it may concern:

Be it known that I, Charles E. Knox, a citizen of the United States, residing at Enid, in the county of Garfield and State of Oklahoma, have invented a new, original, and ornamental Design for a Merchandise Cabinet, of which the following is a specification, reference being had to the accompanying drawing, forming part thereof.

I claim:

The ornamental design for a merchandise cabinet, as shown.

CHARLES E. KNOX.
